BEVERAGE COOLER

Walter L. Pieschel, Ludlow, Ky., assignor to The Coca-Cola Bottling Works Company, Cincinnati, Ohio, a corporation of Ohio

Filed Nov. 26, 1963, Ser. No. 77,566

Term of patent 14 years

(Cl. D2—3)

FIG. 1 is a plan view of a beverage cooler showing my new design, the dispensing faucets thereof being shown in dot-dash lines;

FIG. 2 is a front elevational view thereof;

FIG. 3 is a rear elevational view thereof;

FIG. 4 is a side elevational view thereof;

FIG. 5 is another side elevational view thereof; and

FIG. 6 is an enlarged view in section taken on the line 6-6 in FIG. 1, portions thereof being broken away.

The essential features of the disclosed design reside in the portions shown in full lines.

I claim:

The ornamental design for a beverage cooler, as shown and described.
